UNITED STATES PATENT OFFICE.

D'ORSAY McCALL WHITE, OF INDIANAPOLIS, INDIANA, ASSIGNOR TO LA FAYETTE MOTORS COMPANY, OF INDIANAPOLIS, INDIANA, A CORPORATION.

HOOD LATCH FOR MOTOR VEHICLES.

1,414,242.

Specification of Letters Patent. Patented Apr. 25, 1922.

Application filed February 5, 1921. Serial No. 442,768.

To all whom it may concern:

Be it known that I, D'ORSAY McCALL WHITE, a subject of the Kingdom of Great Britain, and a resident of Indianapolis, county of Marion, and State of Indiana, have invented a certain new and useful Hood Latch for Motor Vehicles; and I do hereby declare that the following is a full, clear, and exact description thereof, reference being had to the accompanying drawings, in which like numerals refer to like parts.

This invention relates to hood locks and the like, and the chief object of the same is to provide a hood with enclosed latching means, including an exteriorly positioned operating handle by which the hood may be elevated when the latching means is in unlatching relation and with catch means which when released is movable by gravity into the non-latching relation.

The chief feature of the invention consists in constructing a hood lock such that the latching portions will be positively actuated to latch the hood in closed position and will be positively maintained in said closed hood latching position, but which when released is movable by gravity into the non-latching position.

Another feature of the invention consists in the particular construction of the catch, and the actuating means therefor associated with the handle means and operable thereby.

Other features of the invention consist in the specific construction of the enclosed hood latch and hood elevating handle.

The full nature of the invention will be understood from the accompanying drawings and the following description and claims.

40 In the drawings Fig. 1 is an elevational view of a hood latch with the parts in the hood closing position. Fig. 2 is a longitudinal sectional view taken on line 2-2 of Fig. 1 and in the direction of the arrows.

45 Fig. 3 is an elevational view similar to Fig. 1 but shows said parts in the unlatched or released position.

In the drawings 10 indicates a supporting member such as the chassis channel portion 50 to which is suitably secured an upwardly extending hook or catch 11, said member being detachably secured thereto by suitable bolt and nut means 12. The catch 11 is provided with a hook portion 13. 14 indicates the hood which is provided at its lower

end with the usual bead 15, and in the present instance said hood is adapted to bear against the hook 11.

The hood 14 is apertured to receive a bracket plate 16. Positioned adjacent the aperture and preferably surrounding the same is a reenforcing plate 117. The hood reenforcing plate, hood and bracket plate are secured together in rigid relation by suitable bolt and nut means 18. Thus, the bracket 16 is rigidly supported upon the hood 14. The bracket 16 is centrally apertured at 17 and a shaft 18 is rotatably supported therein. The shaft 18 carries upon one end a circular plate portion 19 and secured thereto or integral therewith is an ornamental handle 20 which is substantially T-shaped.

The bracket 16 is provided with arm means extending angularly thereof and downwardly therefrom, and said arm means is indicated in the drawings by the numeral 21. The bracket arms 21 extend downwardly towards each other and are connected together near their free ends by a transverse plate portion 22. The bracket arms, however, extend beyond said plate portion and provide the parallel bearing portions 23, which bearing portions pivotally support a hook or catch member 24. The hook 24 is pivotally supported in the free ends of said arms by suitable means such as the pivot bolt or pin 25. The free end of the hook 24 extends sidewardly in both directions to provide a plate portion 26 which also projects forwardly of said supporting portion of the hook and is adapted to engage the hook 13 of the catch 11. The body portion of the hook 24 is extended to form a web and a hole 27 is provided in said web.

Upon the inner end of the shaft 18 is suitably secured an eccentric arm 28 which is keyed to said shaft by the pin 29. A coiled spring member 30 has one end secured to the hook 24 by engaging in the opening 27 and the other end is eccentrically positioned with respect to the shaft 18 by being suitably secured by the bolt 31 to the eccentric arm 28. Suitable pin means 32 and 33 limit the rotational movement of the shaft 18 by engaging the eccentric arm 28.

It will be understood that the rotational movement of the shaft 18 by means of the handle 20 will cause the eccentric arm 28 to move to the upper position illustrated in Fig. 1, and thereby through the spring 30 draw

the pivotal hook 26 into engagement with the hook 13 to latch the hood in closed position. The pin 32 being positioned slightly over-center, is adapted to maintain the eccentric 5 arm 28 in the elevated and overcenter position. When the handle 20 is reversely rotated, the eccentric arm 28 is moved from the position shown in Fig. 1 to the position shown in Fig. 3 which thereupon releases the 10 tension upon the spring member 30 and the same contracts into its usual unstrained position. Thus, no upward directing force is exerted upon the hook 26 and the same, therefore, falls due to the influence of gravity 15 thereon from the position shown in Fig. 1 to the position shown in Fig. 3, both of which positions are also shown in Fig. 2. In the present instance to prevent reverse rotation, the stop pin 32 prevents further 20 rotational movement than that shown in Fig. 3, thereby insuring that the arm 28 cannot be continuously rotated but necessitates reverse rotation of the handle 20 to position the several parts in the locking or hood closing position.

While the invention has been described in great detail, it will be readily understood by those skilled in the art that various modifications may be substituted for the several parts 30 herein shown without departing from the broader features of the invention. It is to be understood that the foregoing description is illustrative rather than restrictive in character.

35 The invention claimed is:

1. A hood latch for motor vehicle including a chassis supported latch member positioned within the hood, an engaging member within the hood and supported thereby, and 40 means operable from without the hood for causing said members to engage and latch the hood to the chassis, said engaging member being movable by gravity away from said latching member to the released position 45 when the exteriorly-operated means is moved in one direction and drawn into engagement therewith when said means is operated in the other direction.
2. A hood latch for a motor vehicle, including an automobile hood latching means 50 positioned within the hood, and means for

actuating said latching means, said actuating means being so arranged that when moved in unlatching position it will permit the release of said latching means by gravity, and when moved to the opposite position, it will cause the engagement of the latching means and the latching of said hood.

55 3. In a hood latch for motor vehicles having a latch-supporting plate including a bearing, a depending bracket arm secured within said hood forming a pivotal support, a catch pivotally supported on said bracket arm, a pivotal actuating member extending from without said hood through said bearing, and means connected to said catch and actuating member for drawing said catch into latching position.

60 4. In a hood latch for motor vehicles having a chassis, a latching member secured to said chassis, an actuating handle mounted on the outer side of said hood and extending therethrough, a bracket arm secured to the inside of said hood and forming a pivotal support, a catch pivotally supported by said bracket arm, and means secured to said catch and to said actuating handle for permitting said catch to disengage said latch member when operated in one direction and be drawn into engagement therewith when 70 turned in the opposite direction.

65 5. In a hood latch for motor vehicles having a chassis, a latch member secured to said chassis adjacent said hood, an actuating handle mounted on the outside of said hood and extending therethrough, a downwardly and outwardly extending bracket arm secured to the inside of said hood for forming a pivotal support, a catch pivotally supported by said bracket arm so as to swing downwardly and outwardly away from said hood when released, and yielding means secured to said catch and eccentrically to said actuating handle for permitting said catch to swing by gravity downwardly and away 75 from said latching member when operated in one direction and be yieldingly drawn into latching engagement therewith when turned in the opposite direction.

80 In witness whereof, I have hereunto 100 affixed my signature.

D'ORSAY McCALL WHITE.
